UNITED STATES PATENT OFFICE.

WARREN P. VAN LOAN, OF NEW YORK, N. Y.

BRUSH.

SPECIFICATION forming part of Letters Patent No. 727,035, dated May 5, 1903.

Application filed July 23, 1902. Serial No. 116,723. (No model.)

To all whom it may concern:

Be it known that I, WARREN P. VAN LOAN, a citizen of the United States, residing at New York, in the county of New York and State 5 of New York, have invented new and useful Improvements in Brushes, of which the following is a specification.

This invention relates to brushes, and particularly to means for adjusting the handles 10 of the same; and the object in view is to provide simple and effective means in connection with a brush-head whereby the handle may be moved into various positions to conveniently assist in the use of the brush in corners 15 of floors or angles of walls to facilitate the removal of dirt and dust therefrom.

With this and other objects and advantages in view the invention consists in the construction and arrangement of the several 20 parts, which will be more fully hereinafter described and claimed.

In the drawings, Figure 1 is a central transverse vertical section through a brush and handle-socket attachment embodying the features of the invention. Fig. 2 is a top plan view of a portion of a brush head or back, showing the improved handle-adjusting means applied thereto. Fig. 3 is a perspective view of a part of the adjusting means. 25 Fig. 4 is a transverse vertical section on the line 4-4, Fig. 3.

Similar numerals of reference are employed to indicate corresponding parts in the several views.

35 The numeral 1 designates a brush head or back of any suitable form and provided, as usual, with brush-bristles or other devices 2. The head or back 1 may be of rectangular, oblong, or oval shape, and applied to and 40 firmly secured in place on the upper side of the head or back is an annulus 3, having an inner circumferential groove 4 to provide a shoulder 5. The annulus is radially slotted at regular intervals, as at 6, the several slots 45 converging toward the outer edge of the annulus and having pins 7 extending upwardly from the bottom walls thereof and centrally located in relation to the several slots, a single pin rising from the center of each slot. 50 The annulus is held in immovable connection to the head or back 1 by screws or other analogous fastenings passed therethrough, and

rotatably held by the said annulus on the head or back is a center plate 8, having an integral handle-socket 9, extending upward and outwardly therefrom at an angle of inclination, the said socket being tapered downwardly toward the plate. The plate 8 moves under the shoulder 5, and the fulcrum for said plate consists of a screw pin or bolt 10, passed 60 through the center thereof and the head or back 1, as clearly shown by Fig. 1.

The inner end of a locking-catch 11 in the form of a plate-spring is held on the center plate 8 under the head of the bolt or pin 10, 65 the said locking-catch being long enough to extend outwardly and enter either one of the slots 6 in the annulus 3, and for convenience in operating the said catch the outer end 12 is slightly upturned and projects beyond the 70 annulus. Rising from the plate 8 for engagement by the catch 11 is a stud 13, an opening 14 being formed in the said catch to permit the stud to pass therethrough, and outwardly from the opening 14 is a second opening 15, 75 through which the several pins 7 are also adapted to pass.

A handle of any suitable length is inserted in the socket 9, and in adjusting the said handle the catch 11 is released from the annulus by drawing upwardly on said catch and also from the stud 13, and when the catch is so released the center plate 8 may be turned to bring the socket 9 and the handle therein in the position desired and the catch then 85 permitted to engage the slot 6 nearest thereto and also the pin 7 in said slot. It will be seen that the stud 13 acts as a guide or means for causing the catch to move regularly with the center plate after the said catch has been 90 disengaged from either one of the pins 7, and at such time or after such disengagement has ensued the catch is permitted to become re-engaged with the stud 13 and is turned with the center plate over the upper surface of 95 the annulus and will be held up in passing over the slot 6 preceding that in which it is desired the catch shall rest to attain the adjustment desired. When the catch is in engagement with the stud 13 and either one of 100 the slots 6 and pins 7, the plate 8 will be positively held against movement and the adjustment of the socket 9 and handle therein can be immovably maintained.

Through the medium of the adjustable features set forth a brush head or back may be disposed at any angle for convenience in reaching fully in the corners or angles of a wall and assist in a thorough cleaning operation in relation to a floor or walls.

The outward inclination of the socket 9 disposes the handle in such manner that the brush may be conveniently manipulated in its use, and the outward reduction of the slots 6 renders the operation of the catch 11 more effective.

Having thus fully described the invention, what is claimed as new is—

15 The combination with a brush-back, of an

annulus secured thereon and having radial slots therein with pins projecting upwardly therefrom, a rotatable center plate disposed within the annulus and having a stud rising therefrom, the said center plate carrying a handle-socket, and a spring-catch movable with the center plate and provided with openings to engage the stud and pins. 20

In testimony whereof I affix my signature in presence of two witnesses.

WARREN P. VAN LOAN.
